UNITED STATES PATENT OFFICE.

ALBERT W. MEYER, OF NEW YORK, N. Y.

STEAM-COOKER.

1,089,066.

Specification of Letters Patent. Patented Mar. 3, 1914.

Application filed July 5, 1911, Serial No. 636,814. Renewed July 30, 1913. Serial No. 782,141.

To all whom it may concern:

Be it known that I, ALBERT W. MEYER, a citizen of the United States, and a resident of New York city, in the county of New York and State of New York, have invented certain new and useful Improvements in Steam-Cookers, of which the following is a specification.

My invention relates to steam cookers and the object of my invention is to provide a steam cooker having a cover that is provided with a sealing groove or grooves to effect a tight joint between the cover and body portion, without the use of water, and to have the parts fit sufficiently close to hold together by friction against a moderately low pressure of steam.

A further object is to provide a cover which is light and may be made of sheet metal which is pressed or spun into form at a low cost.

Referring to the drawings which form a part of this specification, the figure is a vertical sectional view through the steam cooker.

A, indicates the pot or body portion and B, the cover therefor. The pot A, is provided with an inwardly extending flange portion C which is provided with an annular groove C' the bottom of which is curved as illustrated. The flange is also provided with another annular groove C² which is preferably made greater in depth than groove C', and the bottom of which is also curved and the innermost portion of the flange at its upper edge C³ extends above the adjacent top plane surface of the flange portion. The flange portion may be made in cast metal and afterward turned to finished condition in a lathe but I prefer to make it by spinning or pressing it from sheet metal.

The cover portion consists of a sheet metal portion B' which is pressed or spun into a form to provide depending annular projecting channeled portions B² and B³ respectively which conform to the shape of the said annular grooves in the flanged portion C, to fit in said grooves closely in contact with the metal of the flange C and terminating in a horizontal rim B³⁰. A second portion of the cover consists of a closing member formed of a sheet of metal B⁴ which contacts with the portion B' over the area above the opening in the pot, and curved at its periph-

ery, terminating in an inwardly extending ring D disposed under rim B³⁰ and forming a tight joint therewith. This closure member B⁴ serves also to cover the channels B² and B³ and prevents the accumulation of 60 dust and other foreign substances therein.

In case only one seal is required the portions comprising the annular groove C' and B² may be omitted.

A cylindrical sheet metal portion E is 65 connected to the portions B⁴ and B' by a screw F, which screws into the knob H, thereby forming an annular groove G in the bottom of which is located packing material G' of cork or other suitable material to 70 form a steam tight joint at this point.

Eye clips I—I are fastened to the sides of the pot at diametrically opposite sides and a helical spring J is fastened to each of said clips at one end, and the other end 75 is fastened to an eye K which is provided with an extension K' projecting at a right angle to the vertical axis of the pot.

On the top of the cover B are two hooks L—L which are fastened by metal clips 80 M—M, and the ends of which project beyond the periphery of the cover to permit the hooks to pass through the openings K² of the eyes, the upturned ends of the hooks preventing the eyes from slipping off accidentally.

When the cover is placed on the pot, the pot becomes sealed by reason of the close fit of the projecting portions of the cover within the annular groove or grooves and 90 by the packing material G' located between the edge C³ of the flange portion and the cover. In case too high a pressure of steam is generated in the pot and the cover is lifted from the pot, the springs J will permit the 95 cover to lift but will prevent it from being blown from the pot entirely since they, with the cover, act as a safety valve for the pot.

Having thus described my invention, I claim as new:

1. A pot having a side wall and an open top, a grooved flange extending from the top of the wall adjacent the opening, and a cover having a plurality of depending annular channeled projections adapted to fit 105 within said grooves, and a horizontally extending rim adapted to rest on said flange, and a closure member located above said channels to cover the same and terminating in an inwardly extending horizontal ring 110

doubled over with respect to the body of said member and adapted to be clamped between said rim and flange.

2. A pot having a side wall and an open top, a flange extending from the top of the wall adjacent the opening and a cover comprising two separate closure members, one of said members having a horizontal rim projecting over the flange and the other of 10 said members being located above said first member and terminating in an inwardly extending horizontal ring adapted to be clamped between said rim and flange.

3. A pot having a side wall and an open 15 top, an annular flange extending inwardly from the top of the wall, and a cover comprising three separate closure members, one of said members projecting into the opening, the second of said members located 20 above said first member and having a horizontal peripheral rim extending over the flange, and the third of said members having an inwardly extending portion disposed between said rim and flange and adapted 25 to be clamped therebetween.

4. A pot having a side wall and an open top, a flange extending from the top of the wall, and a cover comprising two closure

members, one of said members having a horizontal rim projecting over the flange, 30 and the other of said members being located above said first member and terminating in an inwardly extending horizontal ring, located between said rim and flange, and a plurality of springs adapted to clamp said 35 ring between said rim and flange.

5. A pot having a side wall and an open top, a flange extending inwardly from the top of the wall, said flange having an inner upwardly projecting tubular portion and a 40 groove adjacent thereto, a cover having a depending tubular portion fitting within the first mentioned tubular portion, and a depending channeled annular portion adapted to fit within said groove, said cover having 45 also a horizontal rim located above said flange and a flat closure member covering said channel.

Signed at New York city, in the county of New York and State of New York this 3rd 50 day of July A. D. 1911.

ALBERT W. MEYER.
